UNITED STATES PATENT OFFICE.

ALBERT T. FAY, OF OAK PARK, ILLINOIS.

RAILROAD-SWITCH.

SPECIFICATION forming part of Letters Patent No. 276,794, dated May 1, 1883.

Application filed May 15, 1882. (No model.)

To all whom it may concern:

Be it known that I, ALBERT T. FAY, of Oak Park, in the county of Cook and State of Illinois, have invented a new and Improved Railroad-Switch, of which the following is a full, clear, and exact description.

The invention consists of a switch-lever contrivance and apparatus attached to the locomotive for enabling the switch to be shifted by the locomotive or not, at the will of the engineer, the shifting apparatus being contrived to be set by steam for shifting the switch to right or left, the switch being self-locking, and also being so that when open the switch-rails can be shifted by the wheels, so as to pass it in one direction, after which the rails will be shifted back by a spring arrangement in the switch-bar, so contrived for enabling the train coming upon the main line and wanting to back off over the switch to change the switch before passing it, so that after passing the said switch it will be set for backing off on the branch, as hereinafter fully described, and pointed out in the claims.

Reference is to be had to the accompanying drawings, forming part of this specification, in which similar letters of reference indicate corresponding parts in all the figures.

Figure 1 is a plan view of the switch, with a part of the switch-lock in horizontal section. Fig. 2 is a section through the switch lever and lock on the line $x x$, Fig. 1, which is the position of the switch-lever when the switch is set for the siding. Fig. 3 is a section of the switch-rod contrivance for allowing the wheels to shift the switch-rails when the switch is open. Fig. 4 is a side elevation of the said switch-bar contrivance. Fig. 5 is a side elevation of portions of the locomotive, showing the apparatus thereon for shifting the switch by the locomotive. Fig. 6 is a top view of the said apparatus. Fig. 7 is a front elevation. Fig. 8 is a vertical section, and Fig. 9 is a horizontal section of the steam-valve of the apparatus for setting the switch-shifter.

A represents the main line; B, the branch line; C, the switch-rail; D, the point, and E the guard-rail to hold the switch-rail, and thereby prevent the wheels from being turned off on the branch by point D when the switch is set for the main. The point D and switch-

rail C are connected to each other by the rod F, and the switch-rail is connected to the switch-bar G by bar H, between the springs I and J, in a box, K, Figs. 3 and 4, attached to the said bar, which allow the rail to be shifted along the bar, so that when the switch is set for the siding, as represented in Fig. 1, a train moving to the right hand will shift the switch-rail C and point D by the flanges of the wheels, so as to pass the switch safely, and after the train has passed the spring I will set the switch again, so that the train may back onto the branch.

In order to control the switch from the train when the latter is moving in the opposite direction—that is, from right to left—a lever, K', is arranged upon the ties between the rails, to be shifted by a shifter attached to the locomotive acting on the stud L of the lever K', said lever being arranged on a fulcrum-pivot, M, and connected with the switch-bar G by a pin, N. Beyond pin N the end of the switch-lever projects into the lock-case O, to be locked after shifting the switch by the catches P, which are made to engage it by springs Q.

R is a trip-lever, pivoted to switch-lever K' at S, to trip the catches when the switch-lever is to be shifted, said lever having a vertical arm, T, working in a slot of stud L, and being a little wider than said stud, so that it always projects a little beyond the side of stud L, on which the shifter is to act, and is thereby moved far enough before the shifter acts on stud L to enable the bevel-corners V to unlatch the catches and free the switch-lever at the moment when the shifter strikes it. The trip-lever R is located between upper and lower bars of the switch-lever K', and it has slots to receive the pins M and N, which connect these two parts of the lever K' together and permit it to vibrate between the parts of the lever K'. The springs, forming the connection of point C with the box, cushion the shocks when the train, running rapidly, shifts the switch by the lever K' to pass along either the main line or the branch.

The shifter consists of the point-headed bar W, suspended by the shaft X from the steam-chest y, bolted to the under side of the cross-beam Z of the pilot, as shown in Figs. 5 and 7. The upper end of this shaft X has an os-

cillating piston, *a*, working in the triangular steam-space *b*, the steam being admitted to and exhausted from opposite sides of the piston through ports *e*, according as the live-
5 steam cavity *f* or the exhaust-passages *g* of the valve *h* register with said ports *e*. Steam is admitted to cavity *f* through pipe *a'*, having suitable connections with the boiler.

It will be noticed that when the valve stands 10 in the central position, Fig. 8, both sides of the piston *a* are open to exhaust through passages *i*. A movement of the valve to the right will close the exhaust on that side and open steam-cavity *f* to the port *e* of the side, admitting steam to shift piston *a* to the left. 15 The reverse motion of the valve will effect a reverse motion of the piston, and the piston thus swings the shifter *W* to the right or left at the will of the engineer, who works the 20 valve as required by the lever *j*, located in the cab and connected with the valve by the rods *k m* and crank *n*, or it may be any equivalent contrivance.

The dotted lines *o'*, Fig. 6', show the range of 25 the shifter when turned by the steam for passing to right or left of switch-lever *K'* for turning it to open or close the switch. This range is to be limited by a stud-pin, *p*, in the upper side of the front end of the shifter, which will 30 engage stops *o²*, said stops being attached to any part of the engine suitable for arresting the lever and supporting it when it strikes stud *L*.

To return the shifter to the middle position 35 and retain it there, so that it will pass the switch-bar without shifting it, a couple of springs, *q*, are made to bear against said stud *p*, said springs being attached to supports *t*, mounted on a guard, *u*, that is suspended from 40 the locomotive by bars *w*. This guard is for the purpose of preventing the switch-lever from rebounding after being shifted by its edges *w'* holding the lever in position to which it is shifted for a short time thereafter, while 45 said guard is passing stud *L*, to allow the catches *P* time to engage it.

It will be seen that the engineer has by this contrivance command of the switch, whichever way his train may be moving and whichever 50 way the switch may be, whether open or closed,

and the switch can be shifted by hand, if required.

Having thus fully described my invention, what I claim as new, and desire to secure by Letters Patent, is—

55

1. The combination, with the switch-rail *C* and the point *D*, connected together by the bar *F*, of the switch-bar *G*, connected to said switch-rail by a yielding connection, the switch-lever *K'*, the spring-catches *P*, and means for 6c disengaging the said lever from the catches by a passing train, substantially as herein shown and described.

2. The switch-rail *C*, connected to the switch-bar *G* by bar *H*, and spring *I* to allow said 65 rail to be shifted by the wheels, and spring *J* to cushion said rail, substantially as described.

3. The combination of catches *P* and trip-lever *R* with the switch-lever *K'*, arranged to be shifted by the locomotive, substantially as 70 described.

4. The trip-lever *R*, in combination with switch-lever *K'*, arranged with an arm, *T*, wider than the stud *L*, and on pivots located with respect to the pivot *M*, substantially as described, 75 whereby the shifter actuates it before actuating said lever *K'*, substantially as described.

5. The combination, with the switch-lever *K'*, provided with the stud *L*, and the spring-catches *P*, of the trip-lever *R*, provided with 80 the arm *T*, and adapted to be operated by a passing train, substantially as herein shown and described.

6. The combination, with the switch-lever *K'*, the spring-catches *P*, and the trip-lever *R*, 85 provided with the arm *T*, of the suspended shifter *W* and means for operating the same, substantially as and for the purpose set forth.

7. The shifter *W*, mounted on the locomotive, for actuating the switch-lever, and being connected with steam-cylinder *b* and piston *a*, having a reversing steam-valve, substantially as 90 described.

8. The combination of stud-pin *p* and springs *q* with shifter *W*, substantially as described.
